DETACHABLE BLADE BIT

Herbert J. Hawthorne, Houston, Tex.

Application August 24, 1945, Serial No. 612,416

3 Claims. (Cl. 255—61)

1

The invention relates to a detachable blade bit generally known in the well drilling art as a drag bit. With drag bit construction the blade portions wear rapidly by abrasion against the earth formations and it is desirable to replace the blades while retaining or salvaging the body and other portions of the bit. Great difficulty is encountered, however, in securely affixing the blades to the bit body so as to avoid loosening of the blades due to the chattering of the bit.

It is not uncommon to conduct the drilling operation in the rotary method of drilling wells by applying weights approximately ten, twenty or even thirty thousand pounds to the drill bit by lowering the weight of the drill stem or operating pipe onto the bit. When it is considered that the bit may be rotated at fifty to one hundred revolutions per minute while having a tremendous weight of this sort applied to it, it seems obvious that the bit is chattering against the formation. This chatter action tends to loosen all previous types of detachable blade bits with which I am familiar, and the present invention therefore contemplates a particular arrangement of the structure whereby the blades are securely wedged in position and retained against loosening while under use under the most exacting conditions.

It is therefore one of the objects of the invention to provide a detachable blade bit assembly wherein a plurality of blades are applied to a body structure retained in position with a wedge member and the wedge member in turn wedged against the blade by a retainer collar.

It is one of the objects of the invention to provide wedge members which project outwardly from the bit body so as to be wedged in position by a retainer collar.

Other and further objects of the invention will be readily apparent when the following description is considered in connection with the accompanying drawing wherein:

Fig. 1 is a side elevation of a bit constructed in accordance with the invention and showing certain of the parts in sections.

Fig. 2 is a bottom plan view looking up at the bottom of the bit of Fig. 1.

Fig. 3 is a side elevation with certain parts in the wedge member positioned thereagainst.

Fig. 4 is a bottom plan view of the bit body illustrating one of the blades in position and with section of the bit body.

Fig. 5 is a side elevation of one of the blade members.

The drill collar 3 on the lower end of the drill

stem or operating pipe is shown in section as in Fig. 1 as being internally threaded at 4 with a coarse or acme thread. The bit body 5 has a complementary cross thread 6 thereon to be threaded in engagement with the thread 4. To provide a seal and protect the thread 4 and 6 against corrosion and becoming wedged by sediment and foreign matter, a bushing 7 is threaded into the upper end of the bit body and carries a resilient ring 8 which flares outwardly against the wall 9 of the passage through the drill collar.

The bit body 5 has a central passage 10 therein for the flow of drilling mud or flushing fluid through the bit.

15 The bit body is of peculiar construction as best seen in Figs. 3 and 4 in that it has the upper cylindrical portion 11 which flares outwardly at 12 to form a tapered peripheral face. This face, however, is cut away to provide the enlarged notches 14. There may be any desired number of these notches because bits of this type are usually known as two, three or four-way bits, depending upon the number of blades provided. The bit illustrated in the drawing is a three-way bit and there are therefore three of these notches 14 as best seen in Fig. 4. Each of these notches is formed by a substantial right angle 15 adjacent the center portion of the bit so as to provide the outstanding flanges 16, three of which are seen in Fig. 4.

30 The flanges 16 have a surface 20 against which the blade 21 is adapted to be positioned as best seen in Fig. 4. To properly position the blade, a lug 22 is formed in each of the notches 14 and arranged to have the recess 24 in the blade fitted 35 thereto. This interfitting of the recess and the lug properly positions the blade and prevents it from dropping out of the body.

To retain the blade and clamp it in position a geometrical solid wedge member 30 is positioned 40 in each of the notches 14 and arranged to abut the blade 21 as best seen in Fig. 4. This wedge member will be cut away to accommodate the lug 22 and is thus arranged to abut the rear edge 31 of the blade and the forward edge 32 of the notch. Particular attention is called to the fact that the curved surface 33 of this wedge member is not an arc of a true circle but radially flares outwardly somewhat so that the rear heel portion 34 projects beyond the periphery 35 of the flange 16. This projection is also seen in Fig. 1. In this manner the wedge member projects beyond the tapered face 12 of the bit body and is arranged to be engaged by the clamping collar 40 which has the internal frusto-conical

face 41 as seen in Fig. 1. This collar is of substantial length and its lower end 42 extends over the wedge member 30 almost to the base 44 thereof.

The upper end of the collar at 45 is arranged to abut against the lower end 46 of the drill collar 3.

In assembling the bit the blades 21 will be placed in position with the recesses 24 over the lugs 22. The wedge members 30 will then be positioned and the bit body, blades and wedges will have the collar 40 dropped thereover so as to hold the parts assembled. The drill collar is then threaded into position by engaging the threads 4 with the threads 6 and this threading action tends to wedge the collar 40 securely over the blades and wedge members 30 so that the wedging action clamps the blades in position. The construction just described results in a continuous tightening action on the threaded area 20 because the torque applied to the drill stem in rotating the bit tends to make the threads up tighter. The hammer effect or chattering of the bit against and due to the cutting of the formation causes the parts to gradually fit together more closely and this continuous backing up of the bit due to the friction of the blades against the formation insures against loosening of the parts. In actual operation, the bits constructed in accordance with the invention have given exceptional service.

The blade member is shown as having the cutting edge 50 adjacent its center and the outwardly extending cutting area 51 with the gauge cutting edge 52 in a vertical position.

In order to conduct the mud or flushing fluid from the passage 10 a plurality of water courses 53 which terminate in the discharge ports 54 in the lower end of the bit body have been illustrated. One of these water courses is directly in front of each of the blades.

Broadly, the invention contemplates a detachable blade bit where the blades are secured by a wedging action in position upon the bit body by a clamping collar. In this manner the direct thrust of the rotative force of the drill stem and drill collar against the clamping collar is transmitted to the blades and bit body by the clamping collar so that a rigid securing means is provided.

What is claimed is:

1. A detachable blade bit comprising a body for rotation by a drill stem, a blade supporting area thereon, radial notches in said body forming a portion of said area, means disposed in each notch including a blade portion, an internally tapered clamping collar to slidably fit over said body and means, and a driving drill collar threaded onto said body to abut the top of said clamping collar so that the resistance to turning

of the blades against the formation causes the rotation of the drill stem to continuously urge said driving drill collar to force said clamping collar downwardly along said body to exert a wedging action upon said means and interfitting portions on said blades and body to retain said blades on said body against longitudinal thrust in spite of such driving action.

2. A detachable blade bit comprising a body for rotation by a drill stem, a blade supporting area thereon, drag bit blades contacting said blade supporting area, means on said blade supporting area and said blades to retain said blades on said body against rotational movement, an internally tapered clamping collar to slidably fit over said body and said blades, and a driving drill collar threaded onto said body to abut the top of said clamping collar so that the resistance to turning of the blades against the formation causes the rotation of the drill stem to continuously urge said driving drill collar to force said clamping collar downwardly along said body to exert a wedging action upon said blades, and interfitting portions on said blades and body to retain said blades on said body against longitudinal thrust in spite of such driving action.

3. A detachable blade bit comprising a body for rotation by a drill stem, a plurality of blade supporting areas thereon, drag bit blades contacting said blade supporting areas, inter-engaging means on said blade supporting areas and said blades to retain said blades on said body against longitudinal thrust and rotational and turning movements with respect to said body, an internally tapered clamping collar to slidably fit over said body and said blades, and a driving drill collar threaded onto said body above the top of said clamping collar so that the resistance to turning of the blades against the formation causes the rotation of the drill stem to continuously urge said driving drill collar to force said clamping collar downwardly along said body to exert a wedging action upon said means.
